UNITED STATES PATENT OFFICE.

ROBERT J. CARSON AND WILLIS D. SHERMAN, OF DIXON, ILLINOIS; SAID SHERMAN ASSIGNOR TO SAMUEL B. WADSWORTH, CHARLES D. ETNYRE, AND BENJAMIN F. WADSWORTH, OF OREGON, ILLINOIS.

MACHINE FOR MAKING DRAIN-TILE.

SPECIFICATION forming part of Letters Patent No. 326,018, dated September 8, 1885.

Application filed March 9, 1885. (No model.)

To all whom it may concern:

Be it known that we, ROBERT J. CARSON and WILLIS D. SHERMAN, citizens of the United States, residing at Dixon, in the county of Lee and State of Illinois, have invented certain new and useful Improvements in Machines for Making Drain-Tile; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Our invention pertains to machines for making drain-tile, and refers more especially to certain novel mechanism for packing the material in such molds and at the same time boring out the center thereof.

20 The class of tile to which our invention is at present applied is that constructed of a composition which hardens sufficiently from drying, and the usual operation of burning is therefore unnecessary.

25 In the drawings, Figure 1 is a front elevation of a machine embodying our invention. Fig. 2 is a side elevation of the same. Fig. 3 is a section in line $x-x$ of Fig. 2. Fig. 4 is a detail view of the gear for raising or lowering 30 the packer and hopper.

A is the frame of the machine which supports the mechanism hereinafter described.

B is a table, suitably attached to the frame A.

35 C C are the molds, which are cylinders attached in vertical position to the upper side of the table B, and into which cylinders the material for the tile is conveyed by the spout C'.

D D are hoppers to receive the material and conduct it into the molds C. The hoppers D are 40 supported by chains D' from a cross-tree, D², attached to the vertical shafts of the packers E, and have their lower converged ends inserted in the upper ends of the molds C.

E E are packers, having their lower ends 45 furnished with the oblique wings E', so placed that the lateral rotation of the packers E will cause such wings to pack the material in the molds C, and at the same time ride over the material as packed, and will thereby be gradually

raised to the top of such molds. The packers 50 E E are further furnished with transverse stirrers E', at different points on their shafts, the function of which is to distribute the material equally over the internal area of the molds.

The packers E are attached to the frame A, 55 near their upper ends, by means of boxes F, in which the shafts E³ of the packers E are seated with a feathered key, F', by means of which the packer-shafts E³ are free to move vertically. The packer-shafts E³ are rotated by 60 means of sprocket-wheels G feathered thereon and connected by the sprocket-chain G'.

A bevel-gear, H, feathered upon one of the packer-shafts E³, is driven by a bevel-gear, H', on a horizontal shaft, H², (the latter being 65 actuated in any suitable way,) and the rotation of one shaft E³ through the medium of the sprocket-chains G' is communicated to the other packer-shaft.

A shaft, I, is journaled on the frame A 70 transversely to the shafts E³, and between such shafts provided with a pinion, I', which engages a vertical gear-rack, I², depending from the cross-tree D². In the process of packing the molds C the rack I² is carried to the top 75 of the frame A, and when it is required to lower the packer, by means of the crank I³, the pinion I' is rotated, and the latter, by engaging with the gear-rack I², forces the packers to the bottom of the molds C. The same 80 means can be employed to raise the packer, should it become necessary to do so.

K is a horizontal shaft, driven by means of the belt K' from the shaft H². A bevel-pinion, K², on the inner end of the shaft K, engages and rotates a bevel gear-wheel, L, feathered on the auger M.

M M are augers, designed to bore out the center of the tile as the latter are being molded in the molds C. The augers M are hollow 90 cylinders, having a cutting-edge at their upper extremity. They are rotated by means of a sprocket-wheel, N, integral with the gear-wheel L, which wheel N is connected by the sprocket-chain N' to a corresponding sprocket-wheel, N, feathered on the other auger M. The gear-wheel L and sprocket-wheels N are 95 suitably supported by the frame A.

The augers M are seated pivotally at their lower ends in the horizontal plate O, and have collars M' above and below such plate.

A lever, P, is suitably fulcrumed near its center on the arm A' projected from the frame A, and at its inner end is pivotally attached to the center of the plate O, and by means of the lever P the augers M are forced upward into the molds C as the process of boring is being accomplished. The augers M pass upward through corresponding openings in the plate B.

The material removed in the process of boring drops into the hopper S and is carried from thence by means of the elevator T and discharged into the feed-hopper. (Not shown.)

What we claim as our invention, and desire to secure by Letters Patent of the United States, is—

1. In a tile-machine, the combination of the molds C, packers E, and augers M, substantially as shown, and for the purpose described.

2. In a tile-machine, the construction and relation, substantially as shown, of the molds C, packers E, and augers M, for the purpose specified.

3. In a tile-machine, the combination of the molds C, packers E, and augers M, plate O, and lever P, substantially as shown, and for the purpose described.

4. The combination of the molds C, packers E, sprocket-wheels G, chain G', bevel-gears H and H', and shaft H², substantially as shown, and for the purpose specified.

5. The combination of the augers M, molds C, sprocket-wheels N, chain N', gear-wheels K² and L, and shaft K, substantially as shown, and for the purpose described.

6. The combination of the packer E, shaft I, pinion I', frame A, and gear-rack I², substantially as shown, and for the purpose mentioned.

7. The combination of the hoppers D, chains D', cross-tree D², and packers E, substantially as shown, and for the purpose described.

In testimony whereof we affix our signatures in presence of two witnesses.

ROBERT J. CARSON.
WILLIS D. SHERMAN.
